CLAIM

The ornamental design for a solar garden light, as shown and described.

DESCRIPTION

FIG. 1 is a front perspective view of a first embodiment of a solar garden light, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is an enlarged plan view of its top surface;

FIG. 8 is an enlarged plan view of its bottom surface;

FIG. 9 is a front perspective view of a second embodiment of the solar garden light; and,

FIG. 10 is a front perspective view of the lighting component seen in both the first and second embodiments, with the handle shown in a different configuration of use.

The broken lines in the drawings illustrate the portions of the solar garden light, which form no part of the claimed design.

1 Claim, 10 Drawing Sheets
